DESIGN FOR A TOBACCO POUCH

Walter P. Koeller, Chicago, Ill., assignor to Pres-
To-Fill Products Company, Chicago, Ill., a corporation of Illinois

Application October 26, 1934, Serial No. 53,781

Term of patent 7 years

To all whom it may concern:

Be it known that I, Walter P. Koeller, a citizen of the United States, residing at Chicago, Illinois, have invented a new, original, and ornamental Design for a Tobacco Pouch, of which the following is a specification, reference being had to the accompanying drawing, forming a part thereof.

I claim:

The ornamental design for a tobacco pouch as shown,

WALTER P. KOELLER.
